UNITED STATES PATENT OFFICE.

LARKIN J. MILLER, OF REA, MISSOURI.

WIND-CONTROL MECHANISM FOR THRASHING MACHINES.

Application filed November 10, 1924. Serial No. 749,072.

This invention relates to wind control mechanism for blower fan casings for use in the cleaning of grain in thrashing operations and my object is to produce means whereby the direction of the draft may be regulated both in amount and in direction laterally and vertically to accommodate for grains of varying weight and conditions.

It has been found, in actual practice, that grain is frequently not evenly distributed on the riddles or sieves in the shoe, due to the varying conditions of the grain and other causes. With the ordinary construction of the shoe and blower it is impossible to shift the direction of the current of air to properly clean the grain where there is an extra heavy deposit on the riddles.

One of the objects of the present invention, therefore, is to provide strong, durable, efficient, and inexpensive mechanism whereby both the direction and volume of air delivered under the riddles may be readily and easily changed without stopping the thrashing operation.

Another object is to provide means whereby the angle of the riddles may be readily changed from a point exterior to the machine, as distinguished from the present practice of making such adjustments from inside the body of the thrasher.

With the general objects named in view, the invention consists in certain novel and useful features of construction and combination of parts as hereinafter described and claimed; and in order that it may be fully understood, reference is to be had to the accompanying drawing, in which:

Figure 1 is a fragmentary elevational view of a separator with certain parts in vertical longitudinal section to show the wind control and riddle adjusting mechanism.

Figure 2 is a section on the line II-II of Figure 1.

Figure 3 is an enlarged edge view of the mechanism employed to regulate the volume of air entering the opposite ends of the blower casting.

Figure 4 is an enlarged detail to show a part of the wind control adjusting mechanism.

In the said drawing, where like reference characters identify corresponding parts in all of the figures, 1 indicates the pair of longitudinal frame or stringer members constituting a part of the framework of the

thrasher and 2 the sides of said thrasher. Secured to said frame members are a pair of uprights or standards 3 equipped with suitable bearings for the pulley-equipped drive shaft 4 of a blower 5 of any suitable or desired type. In this connection it is to be noted that the blower is mounted within a semi-circular casing or housing 6 partially encircling the blower and terminating in deflectors 7 and 8. The opposite ends of the housing 6 are open and the entry of air therein is controlled by two pairs of semi-circular flat shutters 9 pivoted at their upper corners to the framework of the thrasher and normally held in closed position by means of retractile springs 10 secured at their opposite ends between a pair of ears 11 secured to each shutter 9.

In order to provide means to guard against cross drafts through the blower casing due to high winds at right angles to the separator and also to guard against the entry of foreign material into the blower, a pair of arms 12 project from each side of the thrasher from which are suspended respectively on each side of the thrasher rectangular plates 13 formed near their upper corners with a pair of slotted openings 14 through which the free ends of adjusting chains 15 pass, the opposite ends of said chains being secured to the lower edges of their respective shutters 9. It will be apparent that by this means the operator may readily adjust any of the shutter members to regulate the amount of air permitted to enter the opposite ends of the blower casing 6.

As it is desirable to provide means whereby the air delivered by each half of the blower may be separately adjusted, the blower 5 is divided into two parts by a circular plate 16 located midway between its ends. By this means it will be apparent that the blower in effect constitutes a pair of simultaneously driven blowers, and that the volume of air delivered to either of these fans may be separately and independently controlled.

The shoe 17, which may be of any common or preferred type, as illustrated is adapted to be oscillated on its hangers 18 and 19 by a connecting rod 20 as common in the art. Mounted within the shoe is a riddle or screen 21 having at each of its corners threaded bolts 22 projecting through vertical slots 23 formed in the sides of the shoe

and through the ends of supporting links 24 and 25 respectively mounted at the front and rear ends of the shoe. The opposite ends of said links 24 and 25 are respectively 5 mounted on the extremities of crank arms 26 and 27 pivotally mounted in brackets 28 secured to the underside or bottom of the shoe and equipped at their outer ends with operating handles 29. With this construction 10 it will be evident that the opposite ends of the riddle may be vertically adjusted within the slots 23 from a point exterior of the machine. In order to secure said riddle in any desired position of adjustment, wing 15 clamp nuts 30 are screwed on each of the threaded bolts 22, and by clamping the links 24 and 25 tightly against the sides of the shoe, the ends of the screen are securely maintained in any predetermined position.

20 In this connection it is to be understood that the sides 2 of the thrasher body are cut away (not shown) to permit the operator to reach and operate the wing nuts 30.

Referring again to the fan casing it will 25 be noted that the upper deflector 7 terminates at such point that the current of air is deflected in a plane below that of the riddle. Pivotally secured to the edge of the lower deflector 8 is a wind board 31, the free 30 edge of said board terminating substantially vertically below the edge of the deflector 7, and the angular position of said wind board may be readily adjusted by means of a pair of ears 32 secured to the opposite ends of the board and each carrying an adjusting screw 33 which bears against the outside face of the deflector 8. By adjusting the screws 33 the angular position of the wind board 31 may be readily changed to vary 35 the angular adjustment of the blast of air to suit the condition of the grain and chaff dropped onto the riddle, as common in the art, it being understood that the purpose of the wind blast is to clean the chaff from the grain by blowing upwardly from below the riddle, the chaff being projected off the back end of the riddle to the stacker (not shown), while any material such as dirt particles or the like, or perhaps a small quantity of the 40 lighter grain drops off the riddle into the conveyor 34 and is again passed through the thrasher, while the grain drops through the riddle to the bottom of the shoe and, due to the oscillation of said shoe, is propelled forwardly and finally drops into the conveyor 45 and is carried to the sacker or grain weighing device, not shown.

As before mentioned, it has been found 50 that the grain, due to varying weight conditions or the character of the straw or methods of feed and the like, will not be evenly distributed when delivered to the riddle, and in order to provide means whereby the blast of air may be laterally adjusted while the 55 machine is in operation to meet these con-

ditions, a series of vertical deflecting blades 36 having flanges 37 pivotally mounted on the wind board 31 are secured at intervals (see Figure 2) for the full length of the board. As heretofore pointed out the blast 70 of air delivered by the blower is substantially that of two separate but simultaneously driven blowers, and in order to provide means for the separate adjustment of each blast, the free or projecting ends of all of 75 the flanges 37 on the right and left sides of the fan division member 16 are respectively pivotally secured to rods 38 and 39 projecting loosely through registering slots 40 in the sides 2 of the thrasher and in spacing 80 blocks 41 mounted on the frame 1, said slots being provided to permit of angular adjustment of the wind board around its hinge point above mentioned. The rods 38 and 39 are normally pressed toward each other 85 by expansion springs 42 and 43 pressing at their opposite ends respectively against the sides 2 of the separator and against the adjacent wind deflector flanges 37. In order to provide means whereby the deflectors may 90 be laterally adjusted, the ends of the rods 38 and 39 are threaded and are engaged with hand wheels 44, whereby the angular positions of the deflectors 36 may be varied against the action of the springs 42 and 43, as will be readily understood, to separately 95 direct the blast of air from the divided blower. It will be apparent that by a greater angular adjustment of one set of deflectors than the other, the major portion 100 of the blast of air can be concentrated on the riddle nearer one side than the other, and that an equal convergence of the deflectors may be effected to concentrate the heaviest force of the blast in the central part 105 of the riddle. It will thus be apparent that the blast of air may be regulated to meet varying conditions and lead to a better grain cleaning action.

From the above description, it will be apparent that I have produced a device of the character described which possesses all of the features of advantage pointed out as desirable, and while I have described and claimed the preferred embodiment of the 110 same, I reserve the right to make all changes properly falling within the spirit and scope of the appended claims.

I claim:

1. In a separator, the combination of a 120 casing having inlet and outlet openings, a blower in said casing, a series of adjustable deflectors secured along the edge of said outlet opening whereby the current of air may be laterally deflected, and means for adjusting said deflector.

2. In a separator, the combination of an open-ended casing having an outlet opening, a blower in said casing, supports projecting beyond the sides of the separator, and guard 130

plate carried by said supports and parallel to but spaced from the ends of said casing.

3. In a separator, the combination of a casing having inlet and outlet openings, a blower in said casing, a series of adjustable deflectors pivotally secured along the edge of said outlet opening; and an operating rod; each of said deflectors being pivotally secured at one of their ends to said rod.
4. In a separator, the combination of a casing having inlet and outlet openings, a blower in said casing, a partition dividing said blower centrally, two series of adjustable deflectors pivotally secured along the edge of said outlet opening, and a pair of

operating rods; the deflectors of each series being respectively secured to one of said operating rods.

5. In a separator, the combination of a casing having inlet and outlet openings, a blower in said casing, a hinged wind board secured along the edge of said outlet to vary the vertical direction of the blast of air set up by said blower, a series of deflectors secured to said wind board for varying the lateral direction of said blast of air, and means for operating said deflectors.

In witness whereof I hereunto affix my signature.

LARKIN J. MILLER.
